SUN LAMP

William J. Lommel, Covington, Ky., assignor to Institutum
Divi Thomae Foundation, Cincinnati, Ohio, a corpora-
tion of Ohio

Filed Dec. 26, 1961, Ser. No. 68,052

Term of patent 3½ years

(Cl. D48—20)

Fig. 1

Fig. 2

Fig. 3

FIG. 1 is a front elevation of the sun lamp of my new design.

FIG. 2 is a side elevation thereof, the opposite side being identical.

FIG. 3 is a perspective view thereof.

The undisclosed rear is substantially flat and plain except for conventional fastening means.

I claim:

The ornamental design for a sun lamp, substantially as shown and described.
